MANUFACTURE OF ORGANOLEAD COMPOUNDS

Sidney M. Blitzer and Tillmon H. Pearson, Baton Rouge, La., assignors to Ethyl Corporation, New York, N. Y., a corporation of Delaware

No Drawing. Application March 28, 1955
Serial No. 497,382

5 Claims. (Cl. 260—437)

This invention relates to a process for the manufacture of organolead compounds. In particular, this invention is directed to an improved process for the manufacture of tetraethyllead.

The process employed in present commercial practice for the manufacture of tetraethyllead has been in use for a number of years and, in general, is satisfactory. However, it has certain disadvantages which are overcome by practicing our invention. It proceeds by reacting a sodium lead alloy, of composition controlled to correspond substantially to NaPb, with ethyl chloride according to the following equation

With the highest yields obtained thereby, only about 22 percent of the lead present in the NaPb alloy is converted to tetraethyllead. Under conditions of best operation of this process, no one heretofore, as far as we are aware, has been able to increase this yield of tetraethyllead by even a few percent, due to the inherent limitation in yield as is apparent from the consideration of the above equation. It should be noted that in this reaction at least 75 percent of the lead originally employed is not alkylated. Thus, in this reaction, large quantities of lead must be recovered and reprocessed to NaPb alloy in order to make it economical. A further disadvantage of such a large quantity of unreacted lead is that valuable reaction space in the reaction vessel is occupied by materials which are essentially inert for the manufacture of tetraethyllead under present conditions and mode of operation.

Other processes for the production of organolead compounds, and in particular tetraethyllead, have been devised to consume the lead produced in the above equation. While such processes are satisfactory from the standpoint of lead consumption, they suffer an additional drawback in common with the present commercial process in that they require organo halide as the ethylating agent. One such process is that described in U. S. Patent 2,535,190 wherein lead as, for example that produced in the commercial process, is treated with metallic magnesium and ethyl chloride in the presence of a catalyst, preferably an alkyl ether. Thus, in this process as well as the present commercial process, the tetraethyllead manufacturing operation is restricted by the necessary balance between the metallic sodium required and the organic chlorine in the ethyl chloride. A classical method for the manufacture of tetraethyllead which likewise requires strict balance between metallic sodium and organic halide, and has the additional drawback of requiring highly hazardous ether in the reaction of the so called Grignard reagent, for instance ethyl magnesium chloride with lead chloride.

It is therefore an object of this invention to provide a process for the manufacture of organolead compounds which overcomes the above objections to the present commercial process and those processes which have been proposed more recently as an improvement thereover.

2

Particularly, it is an object of the invention to increase the conversion of lead to tetraethyllead above that obtained in present commercial practice without requiring the use of metallic sodium, metallic lead, or alkyl halogen compounds.

These and other objects of this invention are accomplished by reacting a lead halide with a metallo organic compound of the alkaline earth metal series selected from the group consisting of beryllium, magnesium, calcium, strontium, and barium, and wherein said metallo organic compound contains only alkaline earth, carbon, and hydrogen atoms.

In accordance with this invention, it has been discovered that to produce organolead compounds it is unnecessary to start with a lead alloy, or in fact to employ metallic lead at all.

The process of the present invention can best be understood by considering the chemical equation involved. In general, the process proceeds according to the equation

where R is an organic radical and X is a halogen having atomic weight greater than 35, that is chlorine, bromine, and iodine, and M is an alkaline earth metal selected from the group consisting of beryllium, magnesium, calcium, strontium, and barium. In the preferred embodiment of this process the organic radicals are hydrocarbons and particularly are non-aromatic or aromatic radicals. Among the non-aromatic radicals we can employ alkyl or hydrocarbon substituted alkyl radicals. In general, we prefer the lower alkyl radicals having up to about eight carbon atoms. Among the aromatic radicals which can be employed in the above reaction are included phenyl and hydrocarbon substituted phenyl radicals having up to 10 carbon atoms are satisfactory. Thus, the compounds MR_2 may be considered alkylating or arylating agents with respect to the lead in the inorganic lead compound.

Of greatest current importance from a commercial standpoint is the manufacture of tetraethyllead by the process of this invention. This embodiment can be illustrated by reference to the following equation representing the preferred embodiment.

Illustrative of the alkylating or arylating agents which we can employ are dimethyl beryllium, dimethyl magnesium, dimethyl calcium, dimethyl strontium, dimethyl barium, diethyl beryllium, diethyl magnesium, diethyl calcium, diethyl strontium, diethyl barium, diethyl beryllium, dipropyl magnesium, dipropyl calcium, dipropyl strontium, dipropyl barium, dibutyl beryllium, dibutyl magnesium, dibutyl calcium, dibutyl strontium, dibutyl barium, diamyl beryllium, diamyl magnesium, diamyl calcium, diamyl strontium, diamyl barium, and the like up to about diethyl beryllium, diethyl magnesium, diethyl calcium, diethyl strontium, diethyl barium, diphenyl beryllium, diphenyl magnesium, diphenyl calcium, diphenyl strontium, diphenyl barium, dibenzyl beryllium, dibenzyl magnesium, dibenzyl calcium, dibenzyl strontium, dibenzyl barium, ditolyl beryllium, ditolyl magnesium, ditolyl calcium, ditolyl strontium, ditolyl barium, diphenethyl beryllium, diphenethyl magnesium, diphenethyl calcium, diphenethyl strontium, diphenethyl barium, dibutylphenyl beryllium, dibutylphenyl magnesium, dibutylphenyl calcium, dibutylphenyl strontium, dibutylphenyl barium, diethylphenyl beryllium, diethylphenyl magnesium, diethylphenyl calcium, diethylphenyl strontium, diethylphenyl barium, and the like. In addition to the normal alkaline earth organo compounds indicated heretofore, the branched chain isomers can be employed. Likewise, a mixture of two or

more compounds MR_2 can be employed along with a redistribution catalyst to produce organolead compounds containing a multiplicity of hydrocarbon radicals. Thus, by employing a mixture of dimethyl magnesium and diethylmagnesium and conducting the reaction in the presence of a small quantity of catalyst such as aluminum chloride, the product comprises a mixture of tetramethyllead, ethyltrimethyllead, dimethyldiethyllead, methyltriethyllead, and tetraethyllead in an equilibrium proportion. Likewise, mixed compounds of the alkaline earth series can be employed to provide mixed organolead compounds. Thus, when methyl phenyl magnesium is employed in the process of this invention, the principal product is dimethyl diphenylead.

Among the preferred lead salts, as shown above, are lead chloride, lead bromide, lead iodide, lead bromochloride, lead chloride, and lead bromoiodide. Other lead halides can likewise be employed with satisfactory results.

By the process of this invention, as much as 50 percent of the lead in the foregoing lead salts is directly converted to organolead or in particular, in a commercial embodiment, to tetraethyllead. The remaining portion of the lead is in a highly active form as lead metal and is ideally suited for employment in the commercial process employing sodium-lead alloy or in that which proposes the reaction of metallic lead with an alkylating agent in the presence of magnesium and a catalyst. Conversely, the lead so produced by this invention can be recycled economically to the present process by conversion to the appropriate lead salt.

Our invention is adaptable to the production of organolead compounds generally, such as tetraethyllead, tetramethyllead, dimethyldiethyllead, tetraphenylead, triethylphenylead and tetrapropyllead. Nevertheless, for convenience in describing our invention hereafter, specific reference will be made to tetraethyllead, the most widely known because of its use as an antiknock agent. Whenever, in the following description, this material is referred to, it is to be understood that other organolead compounds or mixtures can be made by our process. Likewise this invention is adaptable to employing broadly the organo alkaline earth compounds defined heretofore. However, for convenience, specific reference may be made hereinafter to using diethyl magnesium as this is the preferred embodiment in manufacturing the important antiknock material tetraethyllead.

Generally, the process of this invention is conducted as follows. Into a reaction vessel, preferably a stirred autoclave, is placed the desired quantity of an inert liquid carrier such as, for example, a hydrocarbon of medium boiling range. The lead halide in finely divided solid form is introduced through a hopper containing a plug cock into the autoclave while agitating to create a suspension thereof in the inert carrier. A suspension of the organo alkaline earth compound in an inert liquid carrier is then fed to the reactor. The autoclave is sealed and moderate heat is applied while continuing the agitation. Contrary to expectation, the two solid phases commence to react as the temperature is increased. Thereupon, an exothermic reaction ensues and upon reaching the desired reaction temperature, cooling is provided through a jacket in the autoclave. In contrast to other processes for the manufacture of tetraethyllead, when this invention is employed it is not necessary to provide expensive and complex reflux equipment as, by proper choice of the carrier liquid, the reaction can be conducted in a closed system. Thus, tetraethyllead can be produced without the co-presence of ethyl chloride or diethyl ether in the closed vessel. This greatly facilitates control of the reaction and prevents the existence of an otherwise hazardous operation. After completion of the reaction, the organolead compound produced is in solution in the carrier liquid and the other products, namely the alkaline earth salt and metallic lead can be removed by filtration

and the organolead compound removed from the carrier by distillation.

The operation described above can be varied and it is not intended that this invention be limited to the specific sequence of addition of the reactants. For example, the suspension of the organo alkaline earth compound can be added to the reactor first and then the finely divided lead salt added thereto with agitation. Other modifications will be evident.

10 While the above operations were discussed in connection with a batch operation, they can be successfully adapted to a continuous process. In addition to applying the above operation to a continuous process, other modifications of a continuous process can be made, such as first mixing together all the reaction materials and then passing them continuously through a suitable reaction zone.

It has been indicated that the process of the present invention is conducted in the presence of an inert carrier liquid. Hydrocarbons of appropriate boiling point with respect to the organolead compound produced are satisfactory and can be chosen so as to provide a solution of the product suitable for other applications or so that they can be readily removed by distillation at a temperature at which the organolead compound will not decompose. Other inert carrier liquids are satisfactory and where the product is a liquid such as, for example, in the manufacture of tetraethyllead, the organolead compound itself can be employed as a carrier liquid. In such an operation, economics are effected by obviating the necessity of recovery by other means than merely filtration of the co-produced solids. Another class of carrier liquids comprises the liquid amines and liquid ammonia. The principal criterion of choice therefore, of a carrier, is the physical characteristic of the organolead compound produced, and the inertness of the liquid to the organo alkaline earth reactant. Certain of the aforementioned reactant carriers, while inert to the reactants, exhibit a beneficial effect on the reaction which may be considered catalytic in nature and contribute to the ease of reaction and rapidity of arriving at completion of the reaction at relatively lower temperatures and pressures.

In general, when conducting this process in the presence of a liquid carrier as above, the amount of carrier should be proportioned so as to provide adequate heat removal facilities. In general, the load on the heat transfer medium is proportional to the concentration or relative proportion of the reactants and carrier. In a batch operation it is preferred to employ the liquid diluent in the proportion of as much as 1,000 parts per part of organo metallic reactant. In a continuous operation or in an operation providing the maximum heat transfer medium, a more concentrated reaction mixture can be employed wherein as little as equal parts by weight of carrier and organo metallic reactant are employed. In general, it has been found that a more concentrated reaction mixture provides a rapid reaction and, provided adequate heat removal means are provided, this is an advantage as the organolead product is subjected to the elevated reaction temperature for the shortest practical time thereby minimizing thermal decomposition or undesirable side reactions.

The alkaline earth organo compounds employed in the process of this invention can be prepared by methods well known in the art. For example, diethyl magnesium is prepared by reacting ethyl chloride with magnesium turnings in the presence of diethyl ether. Dioxane is then added to the reaction mixture thereby precipitating the halides and leaving a solution of the desired diethyl magnesium in the organic phase. If desired, the low boiling ether can be removed to provide a solution of diethyl magnesium in dioxane. In a more refined embodiment the dioxane can be substantially removed by distillation. For convenience in handling, and to provide a safe operation, tetraethyllead is first added to the

solution prior to the distillation. Thus, a mixture of diethyl magnesium in tetraethyllead is provided which can be employed particularly for the manufacture of tetraethyllead. For certain of the other alkaline earth metals, the organo derivatives are prepared by the direct reaction of alkaline earth metal, preferably in the form of turnings, with an organo mercury compound whereby the desired organo alkaline earth compound is directly prepared in a form suitable for use. It is not intended, however, that the scope of this invention be limited to any particular method of producing the hydrocarbon carrying reactant.

This invention can be further understood by the following detailed working example of one method of practicing this invention as directed to the manufacture of tetraethyllead.

Example I

To a reactor equipped with internal agitation, external heating means, and a means for cooling was added 87 parts of toluene. Agitation was commenced and 4.17 parts of lead chloride of particle size less than $\frac{1}{32}$ inch were added to the toluene. With continuing agitation, the reactor was flushed with nitrogen and a solution of 1.48 parts of diethyl magnesium in 30 parts of a 50/50 mixture of dioxane and diethyl ether was added to the lead chloride suspension. The reaction proceeded at room temperature while under a nitrogen atmosphere and was continued for a period of 69 hours. At the end of this period a minor proportion of water was added to destroy excess diethyl magnesium. The mixture was filtered to remove solids which are processed for lead value. The filtrate was washed with an equal volume of water. The organic layer was then transferred to a still where, by vacuum distillation, the diethyl ether, dioxane, and toluene were removed from the tetraethyllead. Tetraethyllead was recovered in high yield essentially pure.

In general, the reaction of this process is completed within a relatively short period at elevated temperatures, but a somewhat longer time is required at lower temperatures. In general, a reaction time of between about one-half to twenty hours is employed. In particular, in the manufacture of tetraethyllead with diethyl magnesium and lead chloride, we prefer to employ a reaction time of about ten hours or less.

The pressure employed in the reaction vessel is not critical and is usually the autogenous pressure created by the carrier liquid at the temperature employed. Since organolead compounds are relatively toxic, it is desirable to employ a closed vessel in conducting this reaction which may create an elevated pressure if low boiling carrier liquids are employed.

The temperature required to initiate the self-sustaining reaction of this invention varies with the organolead compound being produced. In general, with the lower alkyl lead compounds such as tetraethyllead, it is preferred to employ temperatures in the range of 25° to 150° C. With aryllead compounds, for example tetraphenyllead, it is preferred to operate in the range of 50° to 150° C.

While it was indicated above that in general a catalyst is not required for the practice of this invention, certain materials do exhibit a catalytic effect upon the reaction and, in many instances, their inclusion in the reaction provides a smoother operation. Typical of such materials are heavy metal iodides as well as iodine itself, organic iodides, certain ketones such as acetone and methyl ethyl ketone, organometallic compounds and ethers and amines as indicated heretofore.

The following detailed examples serve to illustrate additional specific embodiments of the present invention. However, the invention is not intended to be limited thereto.

Example II

The reactor comprises an autoclave with internal agitation, external heating means, and a means for cooling.

Attached to the top thereof is provided a hopper for containing solid reactant having a plug cock by which the solid reactant is admitted into the autoclave. The autoclave is flushed with dry nitrogen. Then 160 parts of n-hexane are added thereto. Agitation is commenced and 800 parts of lead chloride of particle size less than $\frac{1}{16}$ is added from the hopper to the n-hexane. To the suspension thus formed are added under dry nitrogen a solution of 3 parts of diethyl magnesium in 60 parts of a 50/50 mixture of dioxane and diethyl ether. The autoclave is sealed and the mixture heated to 110° C. Since the reaction is exothermic cooling is applied to maintain the reaction mixture between 110° to 118° C. When the reaction proceeds, alternate heating and cooling is applied as required to maintain this temperature for a total period of 5 hours. At the end of this period, agitation is stopped and the reaction mixture is cooled to room temperature. The solids are filtered from the reaction mixture, water is added to the filtrate with cooling to destroy excess diethyl magnesium and then the mixture is washed with an equal volume of water. The organic layer is decanted and distilled by vacuum distillation for removal of the hexane, diethyl ether, and dioxane. Tetraethyllead is recovered in high yield.

In place of the hexane employed in the foregoing example as an inert carrier liquid, equally good results are obtained when toluene, xylene, triethyl amine, or diphenyl are employed. In addition to the ingredients specified in the foregoing example, thermal stabilizers may be employed, such as for example naphthalene and styrene to permit operation of the reaction at still higher temperatures without concomitant decomposition of the tetraethyllead so produced.

Example III

When following the procedure of Example II, diethyl beryllium is reacted with lead bromide in essentially stoichiometric amounts in benzene at 90° to 100° C. for six hours to produce tetraethyllead in high yield and purity.

When substituting lead iodide in the foregoing example, the reaction proceeds satisfactorily at temperatures in the range of 60° to 100° C. or at the atmospheric reflux temperature of a C₆ to C₈ hydrocarbon petroleum fraction.

Example IV

When diphenyl magnesium is reacted with lead chloride according to the procedure of Example II, but at a temperature between 120° and 130° C., tetraphenyllead is obtained in high yield.

Example V

Diamyl barium is reacted with lead chloride according to the procedure of Example II. Tetraamylead is obtained in high yield.

Equally good results are obtained when diamyl strontium is substituted for diamyl barium in the above example.

The following example will demonstrate one embodiment of this invention wherein the organolead compound produced is used as a diluent.

Example VI

The procedure of Example II is repeated with exception of the following: the diethyl magnesium solution has added thereto 60 parts of tetraethyllead and then this mixture is subjected to distillation for substantial removal of the diethyl ether and dioxane. The autoclave is charged with 160 parts of tetraethyllead in place of the n-hexane. The reaction is then conducted as described. Tetraethyllead is recovered in high yield.

A particularly advantageous and preferred method of utilizing the process of this invention as specifically directed to a commercial method of manufacturing tetraethyllead comprises starting with free magnesium and

hydriding to produce the corresponding magnesium hydride as the first stage. A second stage then comprises reacting said hydride with ethylene preferably in the presence of a solvent suitable as a carrier for the ethyl magnesium, which is thereafter reacted with the lead chloride in accordance with the foregoing description of the present invention.

We claim:

1. A process for the manufacture of hydrocarbon lead compounds which comprises reacting a metallo hydrocarbon compound containing only the elements carbon, hydrogen, and an alkaline earth series metal where-in each hydrocarbon radical has up to about 10 carbon atoms inclusive and is selected from the group consisting of alkyl and aryl radicals with a lead halide of a 15 halogen selected from the group consisting of chlorine, bromine and iodine.

10

5

2. The process of claim 1 wherein the alkaline earth series metal is magnesium.

3. The process of claim 1 wherein the reaction is conducted in the presence of an inert carrier liquid and at a temperature between about 25 to 150° C.

4. A process for manufacture of tetraethyllead which comprises reacting diethyl magnesium with lead chloride.

5. The process of claim 4 wherein the reaction is conducted in the presence of an inert carrier liquid and at a temperature between about 25 to 150° C.
